UNITED STATES PATENT OFFICE.

WALTER SPOFFORTH, OF ST. PAUL, MINNESOTA.

SOUND BOX FOR SOUND-REPRODUCING MACHINES.

Application filed October 17, 1919. Serial No. 331,433.

To all whom it may concern:

Be it known that I, WALTER SPOFFORTH, a subject of Great Britain, residing at St. Paul, in the county of Ramsey and State of 5 Minnesota, have invented new and useful Improvements in Sound Boxes for Sound-Reproducing Machines, of which the following is a specification.

This invention relates to improvements in 10 sound boxes for sound reproducing machines, the primary object being to amplify sound and to produce clearer reproduction thereof than heretofore. A further object is to provide a sound box which performs the above 15 functions efficiently and by simple and effective construction. With these and other objects in view my invention comprises the features of construction and combination of parts hereinafter more particularly described and claimed.

In the accompanying drawing forming part of this specification, Fig. 1 is a side elevation of my improved sound box; Fig. 2 is a section taken on the line 2—2 of Fig. 25 1; Fig. 3 is a side elevation of the sound board when removed from the sound box; Fig. 4 is a side elevation of one of the spider elements for supporting the sound board in the sound box; Fig. 5 is a section 30 of a detail showing the construction by which the sound board is removably secured in the sound box, and Fig. 6 is a plan of the needle or stylus support which assists in transmitting the vibrations of the needle or 35 stylus to the sound diaphragms.

More particularly my invention relates to that classs of sound boxes which employs a plurality of sound diaphragms whereby greater sensitiveness and louder reproduction of sound is accomplished. In the exemplification of my invention illustrated by the drawing, two parallel sound diaphragms 10 and 11 are clamped securely in a rigid circular casing 12, said diaphragms being spaced apart to form a sound chamber A within the structure which is connected with a duct in the neck piece 13 on the casing. This neck piece is adapted to be joined to the usual tone arm of a sound reproducing machine, not illustrated, in any convenient manner. Arranged within the sound chamber is a sound board B, which is positioned parallel with and centrally between the two diaphragms said sound board being less in diameter than the inner diameter of the casing 12. The sound board and sound dia- 40 phragms are held rigid in the position stated in the following manner: A pair of circular spider frames 14 and 15 similar in construction and formed with shoulder pieces 60 16 on their inner ends engaging over the periphery of the sound boards have their outer ends 17 seated in pairs of ring collars 18 and 19 made out of hard rubber or any other suitable material which fit closely 65 within the circular casing 12. The sound diaphragms 10 and 11 rest with their edges between these rings and in turn are held inwardly by a pair of retaining rings 20 and 21, threaded into the casing 12. In this manner the sound diaphragms and sound board are all clamped inwardly under tension most effectively and in a simple manner.

Poised on knife edges 25 and 26 which are arranged in the same plane occupied by the sound board is the needle or stylus point support 27, which removably supports the needle or stylus 28 in a socket 29, said socket being formed on the lower side of said support and said needle or stylus being detachably secured in the usual manner in said socket by a thumb screw 30. Connected with the needle or stylus support 27 are a pair of sound vibration transmitting girders 37 and 38, the outer ends of which are secured 80 in the usual manner to the central portions of the two sound diaphragms 10 and 11 there being one bar for each diaphragm out of contact with the casing 12. The needle or stylus support is held poised upon the knife 85 edges 25 and 26 under tension by means of the springs 32 and adjusting screws 31. These screws 31 pass freely through the springs and the needle or stylus support and are secured in the lower portion of the 90 casing 12 in the usual manner. By this construction the needle or stylus support is free to vibrate as the needle or stylus travels in the sound record groove and to transmit the sound vibrations caused by the sound record 95 groove to the sound diaphragms, said sound reproduction being greatly amplified by the use of two sound diaphragms. This sound which is produced in the sound chamber within the sound box is improved in 100 quality by the use of the sound board B, said sound board vibrating in synchronism with the sound diaphragms and producing finer tone quality in the duct leading from the sound chamber. The spaces between the 105 diaphragms and adjacent sides of the sound board forming the sound chamber A are 110

connected with the duct in the neck piece 13 by port passages 35 in the spider rings 14 and 15.

In accordance with the patent statutes I 5 have described the principles of operation of my invention together with the apparatus which I now consider to represent the best embodiment thereof, but I desire to have it understood that the construction shown is 10 only illustrative and that the invention can be carried out by other means and applied to uses other than those above set forth within the scope of the following claim.

Having described my invention, what I 15 claim as new and desire to protect by Letters Patent is:—

A sound box for sound reproducing machines, comprising, a cylindrical casing forming an enclosure having a sound transmission duct in its side, a pair of substantially parallel sound reproducing diaphragms 20 in and combining with said casing to form

a single sound chamber connected with said duct, a sound board in and of smaller diameter than the bore of said chamber and 25 positioned actively between said diaphragms, a pair of spider frame supports for holding said board spaced from and between said diaphragms and distanced inwardly from the side of said casing so that free passage of 30 air at the circumference of said board is permitted through the spider frames, non-vibrant rings fitted into said casing for seating the outer ends of said spider frames and diaphragms in said casing without readily 35 conducting sound vibrations, means for clamping said frames, diaphragms and rings tightly in said casing and vibration creating means associated with said diaphragms.

Signed at St. Paul, in the county of 40 Ramsey and State of Minnesota, this 2nd day of October, 1919.

WALTER SPOFFORTH.
